DISPLAY BLISTER FOR A PACKAGE OF RIBBON,
PAPER AND BOW OR THE LIKE

Maurice C. Robinson, 16 Shornecliffe, Montreal,
Quebec, Canada

Filed Mar. 27, 1959, Ser. No. 55,226

Term of patent 14 years

(Cl. D58—2)

Figure 1 is a front perspective view of a display blister for a package of ribbon, paper and bow or the like embodying my new design; and

I claim:

The ornamental design for a display blister for a package of ribbon, paper and bow, or the like, as shown.
